[57] **CLAIM**

The ornamental design for a head rest for a back massaging cushion, as shown and described.

DESCRIPTION

FIG. 1 is a perspective view of a headrest for a back massaging cushion showing my new design;

FIG. 2 is a right side elevational view with the strap shown as broken away for convenience of illustration, the left side being substantially a mirror image thereof;

FIG. 3 is a front elevational view thereof;

FIG. 4 is a top plan view thereof, the bottom plan view being substantially identical thereto; and

FIG. 5 is a rear elevational view thereof.
